[57] ABSTRACT

A machine for attaching fabric to a member having a main wall, side walls extending therefrom and fabric retaining and engaging means on the side wall, has a platform movable from an extended to a retracted position relative to a base, with fabric and then the main wall thereon, and the machine has transversely movable lips biased inwardly and located to fold the fabric along the side walls and into engagement with said engagement and retaining means during travel of said members toward retracted position.

The fabric holding member as above defined may be combined with a cover member designed to overlie and contact the tines.

FABRIC APPLYING APPARATUS

This invention relates to apparatus for placing fabric over a body, that is over a wall to be exposed and along the sides thereof. The body will usually be of plastic. The most common use for a device in accord with the invention, is in a brush for removing lint and small particles from clothing or fabrics. For such an application, the fabric is one provided with a slant pile and with the pile filaments all slanted in substantially the same direction so that brushing a fabric in the advance direction of the slanted filaments removes particles from the fabric, and brushing a surface acting as a receptacle for the particles in the reverse direction, removes the particles from the brush. With such an application, the fabric covered body is usually provided with a mating cover member, covering all of the fabric holding body except the fabric covered surface intended to be exposed.

The invention provides apparatus for applying a fabric (preferably padded on the non-exposed side) to a fabric holding member having a first wall to be covered with fabric and side walls extending therefrom, and having adjacent the edges of the side walls, remote from the first wall engagement means for retaining in position fabric covering the wall intended to be covered and extending along the side walls. Preferably the apparatus also provides means for applying over said fabric holding member, a cover covering all but the exposed side and preferably assisting in ensuring the retention of the fabric on the fabric holding member.

The apparatus preferably comprises lips designed to frame the cross-section of the body holding member and to be resiliently biased to define a smaller aperture. The fabric holding member first wall and fabric in registration therewith are caused by the apparatus to pass through the lips which are caused to move outwardly by the members passing therethrough. Acting under the inward bias, the lips fold the fabric about the edges of the first wall, cause it to lie along the transverse walls and cause it to engage and be held by the fabric engaging means on the fabric holding member.

Preferably, the apparatus as described above, also allows the lips to contract over the fabric holding member and with the fabric thereon holds it until the cover member is applied. The apparatus is designed so that when the cover member is applied, the lips are spread to allow mating of the cover member with the fabric holding member and are then maintained spread until the assembled brush is removed.

In drawings which illustrate a preferred embodiment of the invention:

FIG. 1 shows the fabric attaching apparatus in the rest position;

FIG. 2a and 2b show stages in the operation of the apparatus in attaching the fabric;

FIG. 3 shows the fabric holding member, with the fabric attached retained in position;

FIG. 4 shows the arrangement of the apparatus prior to the initiation of the application of the cover;

FIG. 5 shows the cover member applied;

FIG. 6 shows the article removed;

FIG. 7 shows an exploded view of the members; and

FIG. 8 shows a plan view of the fabric shaping members.

As shown in the specific embodiment the device comprises a base 10 defining an upwardly facing bore wherein is slidably a platform 12 biased to the upward position by a compression spring 14 resting at one end on a groove 16 in the platform and at the other end on flanges 18 on the base. For greater steadiness of the platform there is preferably provided a rod 20 like a piston rod extending downwardly from the platform and through a hole in the base member to a recess 22 allowing the necessary retraction of the rod travelling with platform 12. A peripheral ledge is provided in the peripheral lower extremity of the bore to limit the downward movement of the platform at the desired level. The bore near its upper end is enlarged to provide a step 24 for a purpose to be hereinafter described.

The shape of the bore platform, and bore enlargement, in plan view all correspond to the shape of the brush to be produced with dimensional tolerances and clearances required by the operation to be described. The shape of the brush may vary widely from the ovoid shape shown and still be constructed in accord with the inventive apparatus, as hereinafter discussed.

A plurality (here 6) of lips 25 each forming a portion of the general contour, are inwardly biased by compression springs bearing on the housing and on the lip members as shown. The lips are provided with an upper surface sloping downwardly and inwardly to an inner edge to provide a bevel. The lips are designed in their innermost position, as indicated in FIG. 3, to define a closed periphery somewhat smaller than that desired for the brush fabric holding member 26, and as retracted, spaces appear between the side edges of adjacent lip members which increase as the lips are retracted to their widest spacing. In FIG. 1 the lips are retained against their bias by the side wall of platform 12 and the spacing of these lips in the intermediate position is such that their contour defines the desired shape for the brush although there are gaps as aforesaid. As stated, the contour of the lips is designed to be accurate at their intermediate position, as shown in FIG. 1, and it will be appreciated that for the motion required from this intermediate position to wider and narrower positions that the number of lips provided may be as many as is desirable. It is thought that six lips will be a preferable number to combine reasonably continuous support for the fabric with reasonable economy of design, but it will be noted that as few as four and possibly fewer may be used but four is thought to be the minimum. A larger number is useful but will increase the expense.

The lips 25 which are designed to ride on the fabric material are preferably constructed of teflon for low friction and long wearing qualities. The lips in addition to having an innermost position as shown in FIG. 3 have an outermost position, shown in FIG. 6. The fabric holding member will be designed, as shown, having a first wall 30, side walls 32 extending transversely therefrom and preferably, as in this arrangement, extending perpendicular thereto and a hollow plastic construction open at one side, as shown, with four rectilinearly arranged bosses extending from wall 30 in the same direction as walls 32. The head 42 is shaped so that the four bosses may make a friction fit therewith. Here, the head, rectangular in general cross-section, is recessed at each corner as shown, to make a

friction fit with the bosses and releasably retain the fabric holding member in position thereon. As shown, the bosses 43 are seated on the head and are frictionally releasably retained in place by spring loaded balls 44 outwardly biased by a spring in the center portion of the head. The bosses are provided with downwardly extending bores 46 for attachment of the cover member thereto. There is provided for attachment of the fabric, outwardly extending tines 39 peripherally extending outwardly from adjacent the upper edge of the side walls. The outer contour of the side walls is similar to that of the bore and designed to be inset therefrom by the thickness of the fabric and any padding material. The side walls 32 of the fabric holding member extend away from first wall 30 to edges 37.

As will be noted from FIG. 4, 5 and 6 a cover 50 is provided for the brush (which brush is comprised of the fabric holding member, fabric and cover). The cover has an upper wall 52 designed to overlie the brush central bosses with pegs 54 designed to be received in the lower member bores 46 and an outer wall 56 designed to overlie the upper portion of the fabric holding member side wall and fabric and to retain the fabric engaged with the tines 39 to firmly sustain it in position.

The fabric 58 is preferably used with padding 60 although the invention would operate with fabric alone but the fabric is preferably provided with an inner padding layer lending a more pleasing contour to the finished brush as illustrated in FIG. 6.

The fabric 58 with padding 60 attached is cut to a similar shape to the first wall 30 of the fabric holding member but is made sufficiently larger to allow the fabric covering wall 30 to be folded to extend along side walls 32 and inwardly over edge 37. The upper surface of the body is preferably provided with a guide ring 59 designed to center the fabric over platform 12.

The pile fabric which it is preferred to use as the bristle forming member with this invention, is produced by nylon filaments woven through a cotton backing to provide an extent between stitch apertures double the pile length required.

These extents or some are then cut to produce the piles, and these piles are "panned" which is the application of the heated surface to the pile in one sense to produce the required slant or slope to produce brushing when moved in one direction, and cleaning when moved in the other direction.

Inter alia this material may be obtained from Collins and Aikman Corporation, Ca-vel Division, Ca-vel, North Carolina 27112, U.S.A.

The brush formed in this way has the bristles slanting in one direction, i.e., all of the bristle axes are substantially non-normal to the bristle backing surface and are all displaced by such slope in approximately the same direction from the normal.

In operation, the platform 12 is in the position shown in FIG. 1 and the lips 25 are retained at an intermediate position by the side edges of the platform. With the device in this arrangement, the fabric 58 and padding 60 are placed over the platform 12 with the fabric in contact therewith and centering means 59 as shown is used to properly center the fabric which is designed to centrally provide the area corresponding to the wall 30 of the fabric holding member and to extend

therebeyond to allow enough fabric to extend up the side walls 32 and be folded inwardly over the upper edge 37. The head 42 with the fabric holding member 26 attached thereto, is moved downwardly into contact and in registration with the platform. Downward movement of the three members: fabric holding member 26, fabric 58 and platform 12, slightly retracts the lips 25 and as the platform moves downward the lips 25 act under the biasing pressure supplied by their springs 26 to fold and maintain the fabric and padding extending beyond the edges of wall 30 parallel to the side walls 32 with the members continuing to move downwardly against the upward bias pressure on the platform 12 (supplied by spring 14) from the position shown in FIG. 1 (referring to the dotted fabric outline). As the lips 25 ride opposite the outwardly extending tines 39 along the fabric they press the fabric and padding over the tines causing the fabric and padding to engage the tines and hence to be retained in position. Wrinkling of the folded fabric is minimized due to the tendency of the padding (preferably of sponge rubber or a spongy plastic) to conform to the stress requirements of the fabric. This retention is further increased in the positions shown in FIG. 3, where the upper edges 37 of the fabric holding member has moved downwardly past the plane edges of the inward lips 25 so that the lips 25 under their bias have moved inwardly over the fabric holding member to fold the fabric 58 and padding 60 inwardly thereover. In this position the lips 25 act as shoulders to prevent upward movement of the fabric holding member and the fabric, and the head 42 is withdrawn therefrom, since the frictional retention of the head to the fabric holding member still allows withdrawal separation of the two members.

With the fabric holding member held in this position a new head is provided as illustrated in FIG. 4, preferably by sliding the fabric holding member head to one side and sliding a head 60 complementary to the shape of the cover member, into place.

The mechanism for alternating the two heads over the platform 12 and for properly positioning the heads are not shown as they form no part of this invention, and as many alternative means of performing this will be readily available to those skilled in the art.

The cover member is manually placed with the edges of its side walls located on the chamfered lip walls and the lower ends of pegs 54 in the upper ends of the bores 46.

The head 60 is then caused to move downwardly pressing the cover member so that the wall edges thereof, bearing on the chamfered surfaces of the lips, cause the lips to move backwardly, and, as shown in FIG. 5 the outer walls to bear on the fabric, retaining it in engagement with the tines 39 while telescoping over side walls 32 and while pegs 54 frictionally engage in bores 46.

The cover member now securely holds the fabric in place and is securely attached to the fabric holding member by the posts in the bores and by the overlapping walls and tines. Moreover the side walls of the cover member retain the lips by their edges in retracted position.

Thus when the head is removed the brush with the platform arises under the platform biasing spring pressure and the brush may be removed.

I claim:

1. Means for attaching fabric to the outside of a fabric mounting member having a first wall, side walls each extending transversely therefrom, and means on said side walls for engaging and retaining in position, fabric extending along said side walls at locations spaced from the junction of the side walls with the first wall, comprising;

a base,

a platform slidably mounted on said base to move relative thereto between an extended and a retracted position,

said platform and base being designed so that, in said extended position, the first wall of said mounting member may be placed thereon with fabric between said first wall and said platform, with said fabric being dimensioned to extend beyond said first walls a distance so that when said fabric is folded along said side walls it will contact and be retained by such engaging and retaining means,

a plurality of inwardly biased lips each mounted to move slidably relative to said base, over a range of movement in a direction having its major component transverse to the direction of relative movement of said platform relative to said base, said range of movement of said lips including an intermediate position wherein said lips corresponding to the contour of such side walls adjacent said first wall when said side walls are covered by said fabric;

said lips being located and designed to engage fabric, travelling with said platform and said fabric from the extended toward the retracted position, and under said bias to press said fabric along said side walls and into contact with said engaging means.

2. Means for attaching fabric to the outside of a fabric mounting member having a first wall, side walls each extending transversely therefrom, and means on said side walls for engaging and retaining in position, fabric extending along said side walls at locations spaced from the junction of the side walls with the first wall, comprising;

a base,

a platform slidably mounted on said base to move relative thereto between an extended and a retracted position,

said platform and base being designed so that, in said extended position, the first wall of said mounting member may be placed thereon with fabric between said first wall and said platform, with said fabric being dimensioned to extend beyond said first walls a distance so that when said fabric is folded along said side walls it will contact and be retained by such engaging and retaining means,

means for folding fabric travelling with said platform and said fabric mounting member from the extended toward the retracted position, comprising lips, slidably mounted on said base to move relative thereto in a direction having a component transverse to the direction of relative movement of said platform relative to said base, said lips being located and designed to be inwardly biased and deflectable outwardly by the movement of said fabric mounting member fabric and platform in the retraction direction, to press said fabric against said side walls, said lips being designed on the passage by said engagement and retaining means

of said lips, to cause engagement of said fabric with said engagement and retaining means.

3. Means for attaching fabric to the outside of a fabric mounting member having a first wall, side walls each extending transversely therefrom, and means on said side walls for engaging and retaining in position fabric extending along said side walls at locations spaced from the junctions of the side walls, comprising;

a base,

a platform slidably mounted on said base to move relative thereto between an extended and a retracted position,

said platform comprising a surface facing in the extension direction of substantially the shape of the said first wall with side walls extending from such surface in the relative retraction direction,

said platform and base being designed so that, in said extended position, the first wall of said mounting member may be placed thereon in registration therewith with fabric between said first wall and said platform, with said fabric being dimensioned to extend beyond said first walls a distance so that when said fabric is folded along said side walls it will contact and be retained by such engaging and retaining means,

means for folding fabric travelling with said platform and said fabric mounting member from the extended toward the retracted position, comprising lips, slidably mounted on said base to move relative thereto in a direction having a component transverse to the direction of movement of said platform, relative to said base, said lips being located and designed to be inwardly biased and deflectable outwardly against said bias,

said lips being designed and located in the extended position of said platform to bear inwardly under their bias on the platform side walls and to be passed by movement of said platform first surface, said fabric and said mounting member first wall from the extended toward the retracted position of said platform,

whereby said lips act to fold and press said fabric against said side walls and, on travel of said lips past said attachment and retaining means, to cause engagement of said fabric with said engagement and retaining means.

4. Means as claimed in claim 1 wherein the engaging and retaining means projecting outwardly from said engaging and retaining means is embodied by pointed tines projecting outwardly from said side walls, whereby said lips act to press said fabric over said pointed tines.

5. Means as claimed in claim 2 wherein the engaging and retaining means projecting outwardly from said engaging and retaining means is embodied by pointed tines projecting outwardly from said side walls, whereby said lips act to press said fabric over said pointed tines.

6. Means as claimed in claim 3 wherein the engaging and retaining means projecting outwardly from said engaging and retaining means is embodied by pointed tines projecting outwardly from said side walls, whereby said lips act to press said fabric over said pointed tines.

7. A device as claimed in claim 4 wherein said lips are provided by surfaces chamfered to cause said lips to be deflected by members which contact said chamfered surfaces while moving in the retraction direction, whereby, with said fabric mounting member, located on said platform and fabric applied thereto, retained by said tines, whereby a cover member may be applied to said fabric mounting member, where said cover member includes an outer wall designed to overlie and contact said outwardly directed tines, by moving said cover member downward in the retraction direction to cause deflection of said lips outwardly and to move said cover member over and in contact with said tines.

8. A device as claimed in claim 5 wherein said lips are provided by surfaces chamfered to cause said lips to be deflected by members which contact said chamfered surfaces while moving in the retraction direction, whereby, with said fabric mounting member, located on said platform and fabric applied thereto, retained by said tines, whereby a cover member may be applied to said fabric mounting member, where said cover member includes an outer wall designed to overlie and contact said outwardly directed tines, by moving said cover member downward in the retraction direction to cause deflection of said lips outwardly and to move said cover member over and in contact with said tines.

9. A device as claimed in claim 6 wherein said lips are provided by surfaces chamfered to cause said lips to be deflected by members which contact said chamfered surfaces while moving in the retraction direction, whereby, with said fabric mounting member, located on said platform and fabric applied thereto, retained by said tines, whereby a cover member may be applied to said fabric mounting member, where said cover member includes an outer wall designed to overlie and contact said outwardly directed tines, by mov-

ing said cover member downward in the retraction direction to cause deflection of said lips outwardly and to move said cover member over and in contact with said tines.

10. A fabric mounting member shaped to provide a first wall to be covered with bristle forming fabric and having side walls extending therefrom, pointed tines directed outwardly from said side walls, designed to retain fabric pressed thereover.

10 11. A fabric mounting member as claimed in claim 10 combined with a member thereto including an outer wall, said outer wall being designed to overlie tines projecting from the fabric holding member and dimensioned to retain fabric lying between said outer wall and said tines, in engagement with said tines.

15 12. A fabric mounting member in combination with a member as claimed in claim 11 wherein said fabric, on the side adjacent said first wall is provided with a padding layer.

20 13. A fabric mounting member in combination with a member as claimed in claim 11 wherein bores defined in one of said members are arranged to cooperate with and receive posts on the other of said members, on movement of the member which includes an outer wall toward said fabric holding member and wherein said bores and posts are designed so that when said posts are received in said bores, said member which includes said outer wall is attached to said fabric holding member.

25 14. A fabric mounting member as claimed in claim 12 wherein bores defined in one of said members, are arranged to cooperate with and receive posts on the other of said members, on movement of the member which includes an outer wall toward said fabric holding member and wherein said bores and posts are designed so that when said posts are received in said bores, said member which includes said outer wall is attached to said fabric holding member.
